(57) **CLAIM**

The ornamental design for a refrigerator air filter assembly
as shown and described.

DESCRIPTION

FIG. 1 is a front perspective view of a refrigerator air filter assembly according to our design shown in an unclaimed refrigerator, back, right side, left side, top and bottom views of the design showing no claimed portion of the design when in place within the unclaimed refrigerator;

FIG. 2 is a top-front perspective view of the refrigerator air filter assembly of FIG. 1 with portions of the unclaimed refrigerator removed;

FIG. 3 is a front-right perspective view thereof;

FIG. 4 is a front view thereof;

FIG. 5 is a right cross-sectional reference view thereof taken along the line 5-5 in FIG. 4; and,

FIG. 6 is a bottom cross-sectional reference view thereof taken along the line 6-6 in FIG. 4.

The broken line showing of portions of the article form no part of the claimed design; portions of the article between the jagged, spaced pair of broken lines in the figures being removed.

Dash-dot lines adjacent un-shaded areas represent bounds of the claimed design and form no part of the claimed design themselves.

FIGS. 5 and 6 are sectional views for purposes of illustrating relationships between certain structures relative the front vertical plane of the assembly.
